SHIRAS ELECTRIC COMPANY, OF ST. LOUIS, MISSOURI, A CORPORATION OF MIS-
SOURI.

LIGHT-REFLECTOR.

1,073,639.

Specification of Letters Patent. Patented Sept. 23, 1913.

Application filed April 1, 1913. Serial No. 758,279.

To all whom it may concern:

Be it known that we, OLIVER SHIRAS and FRANK X. CHASSAING, citizens of the United States, residing at the city of St. Louis, 5 State of Missouri, have invented certain new and useful Improvements in Light-Reflectors, of which the following is a full, clear, and exact description, such as will enable others skilled in the art to which it appertains to make and use the same, reference being had to the accompanying drawings, forming part of this specification, in which—

Figure 1 is a side elevational view, partly broken away, of our improved reflector. Fig. 2 is an enlarged vertical cross sectional view.

This invention relates to a new and useful improvement in reflectors for concealed electric lamps and is designed particularly for use in lighting banks, libraries, railway stations, public buildings, etc., where it is desired to have the light rays directed in a particular direction.

Our improved reflector may be secured to the molding near the ceiling of the room to be lighted and constitute part of the finish of the room, in which event, the compartment containing the concealed lamps could 30 be continuous around the room or on the beams or partitions, or, shorter sections complete in themselves and containing our invention could be employed as a table or desk lamp the compartment containing the lamps 35 being supported on a suitable standard.

In reflectors of this character, it has been difficult heretofore to clean the reflecting surfaces within the compartments without removing the electric lamps and it is the object of our present invention to construct 40 containing walls in such manner that they may be separated to be cleaned and at the same time enable the glass in the bottom of the compartment to be removed also for 45 cleaning purposes.

In the drawing 1 indicates a back wall which is designed to be secured to the molding of the room, or said back wall may be provided with a lug 2 to which is secured a 50 supporting post or standard 3 shown in dotted lines in Fig. 2.

4 indicates a trough in which the wires 5 for supplying current to the lamps 6 is arranged. These lamps are arranged in suitable 55 sockets and if desired the lamps 6 may

be operated by a pull-cord 7 which passes down through an opening in the glass bottom wall. The upper edge of the wall 1 is preferably folded forwardly and downwardly to form, as at 8, a groove to receive an interlocking flange of the removable cover. Under this groove is arranged a supporting angle 9 soldered or riveted to the back wall 1.

10 indicates a removable cover having an upwardly extending flange 11 at its rear edge which is designed to fit in the groove formed by the folded over flange 8. This cover may be of any shape desired depending upon the number and angular arrangement of the reflecting surfaces 12 secured 70 therein.

If desired, the cover may also have a finishing molding 13 as indicated in dotted lines in Fig. 2. The cover in the accompanying drawing is shown as being curved with an inwardly extending flange 14 on its lower edge which flange is designed to fit under the angle strip 15 on whose horizontal flange the glass bottom wall 16 rests. This 80 glass bottom wall may be provided with reflecting ribs or corrugations, or it may be frosted or clear, as desired. The other edge of this glass bottom wall rests upon an in-turned flange 1^a extending from the back 85 wall 1.

Where the reflector is to be used in long lengths the lamp compartments are divided at intervals, say of twenty-four inches, by partition walls 17 which serve to support 90 the angle 15 and also the ends of the glass bottom wall 16. Where these partition walls are employed, they are cut away for the passage of the wire trough 4. The cover 10 is also made in short lengths, 95 where long sections are employed, each cover preferably terminating coincident with the partition walls.

In practice, if it is desired to clean the reflecting surfaces inside of the lamp compartments, the flange 14 is pulled out from under the angle 15, the cover 10 being sufficiently flexible to permit this and where a molding is employed as a finish to the cover this can readily be done by grasping the 100 molding, or if the reflector is used as a desk lamp, suitable knobs 18 may be employed on the cover for disengaging the flange 14. When the flange 14 is disengaged the cover 105 can be raised until the flange 11 is with- 110

2
drawn from its groove, whereupon the cover becomes detached and may be cleaned at any place desired. When the cover is removed, the glass bottom walls 16 may also 5 be removed by lifting them out of their respective compartments, the holes for the passage of the pull-cords 7 being sufficiently large to permit the buttons on the ends of said pull-cords to pass therethrough.

10 If it is desired to clean the back walls, this can be done by removing the lamps.

In re-assembling the reflector, the glass bottom walls are first put in position, the pull-cords arranged in their openings and 15 the covers placed in position, first by inserting the flange 11 in its groove, then swinging the cover downwardly and springing the flange 14 under the angle 15.

What we claim is:

20 1. A light reflector comprising a lamp compartment, one wall of which has a separable hinged connection to another wall of said compartment, said detachable hinged wall having reflecting surfaces on its inner 25 face and being provided with a locking flange at its free edge which is designed to be sprung into position to lock the detachable wall in place.

25 2. A light reflector comprising a lamp 30 containing a compartment, the back wall of which is provided with a groove along its

upper edge, a detachable wall having a flange fitting into said groove and forming a separable hinged connection, the opposite edge of said detachable wall being provided 35 with a flange designed to be sprung into position to lock the detachable wall into place.

3. A light reflector comprising a back wall having a wire trough secured thereto, 40 said back wall having an inwardly extending flange at its lower edge and a folded over portion at its upper edge, walls extending perpendicularly to said back wall for supporting an angle piece, a glass bottom 45 plate resting upon the bottom flange of the back wall and on said angle piece, and a cover having an edge flanged to engage under the folded over portion at the upper edge of the back wall, said cover having an 50 inwardly extending flange at its opposite edge designed to be sprung under said glass support angle.

In testimony whereof we hereunto affix our signatures in the presence of two witnesses, this 29th day of March, 1913.

OLIVER SHIRAS.
FRANK X. CHASSAING.
